Primary Examiner — George D. Kirschbaum
Assistant Examiner — Natasha Vujcic(57) **CLAIM**

The ornamental design for a LED linear high bay, as shown and described.

DESCRIPTION

FIG. 1 is a front elevational view of a LED linear high bay showing our new design;

FIG. 2 is a rear elevational view thereof;

FIG. 3 is a top plan view thereof;

FIG. 4 is a bottom plan view thereof;

FIG. 5 is a left side view thereof;

FIG. 6 is a right side view thereof;

FIG. 7 is a first perspective view thereof;

FIG. 8 is a second perspective view thereof;

FIG. 9 is an enlarged view of portion 9 of FIG. 7; and,

FIG. 10 is an enlarged view of portion 10 of FIG. 8.

The broken lines in the drawings illustrate portions of the LED linear high bay which form no part of the claimed design.
